(57) **CLAIM**

The ornamental design for a large central bin drawer organizer, as shown and described.

DESCRIPTION

FIG. 1 is a perspective view of a large central bin drawer organizer, showing my new design;

FIG. 2 is an interior elevational view of one half thereof; FIG. 3 is an interior elevational view of a second half thereof;

FIG. 4 is a top plan view thereof;

FIG. 5 is a bottom plan view thereof;

FIG. 6 is a front elevational view thereof;

FIG. 7 is a rear elevational view thereof; and,

FIG. 8 is a left side elevational view thereof, the right side elevational view being a mirror image of the left side.
